(No Model.)

M. L. POWERS.

MACHINERY FOR GRINDING AND POLISHING THE HANDLES OF CUTLERY.

No. 399,208.

Patented Mar. 5, 1889.

UNITED STATES PATENT OFFICE.

MICHAEL L. POWERS, OF MILLER'S FALLS, MASSACHUSETTS, ASSIGNOR TO
PATRICK O. KEEFE, OF SAME PLACE.

MACHINERY FOR GRINDING AND POLISHING THE HANDLES OF CUTLERY.

SPECIFICATION forming part of Letters Patent No. 399,208, dated March 5, 1889.

Application filed July 26, 1887. Serial No. 245,845. (No model.)

To all whom it may concern:

Be it known that I, MICHAEL L. POWERS, a citizen of the United States, residing at Miller's Falls, in the county of Franklin and State 5 of Massachusetts, have invented certain new and useful Improvements in Machinery for Grinding and Polishing the Handles of Cutlery; and I do hereby declare the following to be a full, clear, and exact description of the invention, such as will enable others skilled in the art to which it appertains to make and use the same.

My invention is an improvement in machinery for grinding and polishing the handles 15 of case or table knives.

One of the important features of my machine is the knife-holder, which consists of a mandrel, having an interior form suitable to the reception of the blade and bolster of the knife, 20 (the end of the former being centerable therein and the latter being held loosely to place,) while the part of the knife—the handle to be operated upon—extends outside of said mandrel and in front of the grinding-wheel. The 25 two parts which form the holding portion of the mandrel are made of spring material, so that the hold taken upon the knife will not be rigid, but yielding, to compensate for the action of the said handle between the grinding-cylinder and the device for holding said 30 handle in contact with said grinding-cylinder. The mandrel is journaled in a loose journal fitted in a slot which, when the capping of said slot is removed, may be taken out if it is 35 desirable to substitute for said mandrel one of a different bolster-notch.

The base, or that portion of the machine which supports and holds the grinding-cylinder, is rigid, and upon said base sets, movable 40 in ways, the carriage which supports and holds the knife-holding mandrel and the several shafts to which are fixed the gear-wheels which transmit motion to the said mandrel and receive motion from the source of power. 45 The shaft which carries the driver of these gear-wheels is provided with an elliptical cam, which twice in a revolution of said shaft gives maximum motion to a bar, guided properly in a slot, on the end of which is pivoted a rocking presser-foot which contacts 50 longitudinally with the knife-handle being

ground, holding it to place against the grinding-wheel; or the movable carriage may have attached to it beneath the mandrel, or at some other convenient point, a cord or belt which 55 rises and passes over a pulley fixed upon a shaft, and at the free end of said belt or cord is secured a weight by which said movable carriage is yieldingly held, with the several parts of the machinery which it carries, to 60 proper position with reference to the grinding-cylinder.

In my drawings illustrating my invention, Figure 1 is a plan or top view of my machine. Fig. 2 is a section on line $x\ x$ of Fig. 1; and Fig. 3 is a section on line $y\ y$ of said figure, 65 looking in the direction of arrow a .

Similar reference-letters indicate like parts in all of the figures.

Referring to the drawings, A is the bed-plate 70 or fixed portion of the machine, to which is fixed uprights R for the support of the grinding-cylinder P. These uprights R are secured by screws $b\ b$ to a base which may be detached from the bed-plate A when it is necessary to 75 substitute one kind of grinding-surface for another. The bed-plate A is provided with cleats A' on its transverse edges to form a dovetail to receive and guide the dovetailed base of the movable carriage B. The carriage B 80 is formed in the main of a skeleton base, e, and upright side blocks, $f\ f'\ f''$, to the latter of which journal-bearings are provided for the several rotary shafts. The bed-plate A is provided with a knee or stop, F, to limit the 85 back movement of the carriage B.

N is the mandrel, fixed on a shaft journaled in a square bearing adjustable in a slot formed in the side block, S, of the carriage B. The mandrel N is bifurcated and its interior is 90 formed in a manner suitable to receive and hold the blade and bolster of the knife to be ground or operated upon. The arms $g\ g$ of this mandrel are made springy. The notch at the base of the mandrel is formed so as 95 to center the knife by the end of the blade, and at the extremity of the mandrel the notch is formed so as to hold the bolster of the knife.

C is a plate fixed to the carriage B, provided 100 with a longitudinal slot which guides a bar, C', having pivoted thereto a presser-foot, D.

A shoulder is formed on the end of the bar C', and the front movement of said bar is limited by a slot, D', formed in the plate C.

K is the driving-shaft of the machine, journaled in the two upright blocks of the carriage and also in a third or intermediate bearing. The shaft is provided with a band or gear-wheel, II, an elliptical cam, G, and a gear-wheel, I. The said elliptical cam contacts with the bar C' as it revolves and throws it toward the grinding-cylinder to cause the presser-foot D to accommodate itself to the irregular form of the knife-handle as the latter is being revolved in front of the said grinding-cylinder.

K' is the mandrel-shaft, provided with gear-wheel M.

L is an intermediate gear-wheel, forming an idler to communicate movement from gear-wheel L to gear-wheel M and the mandrel N. A ring or collar, Q, is provided to clasp the shank of the mandrel and bear against the journal-bearing block O.

When the knife is adjusted to place in the mandrel, the latter is set in motion by means of the several gear-wheels from the source of power, and by suitable means, unnecessary to be shown, the grinding-cylinder is simultaneously revolved. The presser-foot D is kept bearing against the knife-handle during its movement by means of the elliptical cam G, which, during the rotation of the main shaft, bears constantly against the bar to which the presser-foot is pivoted. The presser-foot, by reason of its being readily movable about its axis, yields to the irregular surface of the knife-handle, but at the same time under the influence of the elliptical cam is kept firmly

bearing upon said handle, keeping it up to the grinding-surface of the grinding-cylinder. 40

Having thus described my invention, what I claim as new, and desire to secure by Letters Patent, is—

1. In a machine for grinding and polishing the handles of case or table knives, the revolving mandrel or knife-holder composed of a shank journaled in the supporting-frame and provided with a gear-wheel, and extending from said shank two spring-fingers formed, substantially as described, and adapted to 50 hold the blade of the knife between them while the handle projecting outside of said mandrel is being acted upon by the grinding-cylinder, as and for the purpose set forth. 45

2. In a machine for grinding and polishing case or other table-knife handles, the combination, with the sliding carriage B, held to place by means of a cord and weight, substantially as described, of the bar C', inclosed in plate C, the presser-foot pivoted to said bar 55 and the cam fixed to the driving-shaft, as and for the purpose specified. 6c

3. The combination, with the base or bed plate provided with guide-cleats and having a grinding-cylinder fixed thereon, of the carriage movable upon the said base, the knife-holder or mandrel, substantially as described, the gear-wheels for rotating said knife-holder, and the elliptical cam fixed upon the driving-shaft to operate the presser-foot during the 70 revolution of the knife, substantially as and for the purpose set forth. 65

MICHAEL L. POWERS.
